SHEET METAL STORAGE BATTERY BOX
AND METHOD OF MAKING SAME

Harvey D. Geyer, Dayton, Ohio, assignor to General Motors Corporation, Detroit, Mich., a corporation of Delaware

Application August 4, 1934, Serial No. 738,426

7 Claims. (Cl. 113—120)

This invention relates to a method of making storage battery containers and the resulting product of this method.

An object of this invention is to provide a method of folding up a flat metal sheet to form a multi-cell storage battery container having upstanding side and partition walls which are integral with the bottom walls of the cells.

The flat metal sheet may be first covered with a coating of resilient insulating material (such as soft rubber) and then folded up according to this invention to provide a multi-cell container which has a complete insulating inner lining resulting from said coating. Thus the insulating lining may be readily applied by any well known or convenient method in a more simple and economical manner while the metal sheet is in flat or substantially flat form. Obviously if the multi-cell metal container be first formed the difficulties of subsequently properly applying the inner insulating lining will be greatly increased, particularly if it is necessary to mold said lining to the metal walls of the container. By this invention a resilient coating of soft rubber, or any other suitable resilient insulating material, may be readily and efficiently vulcanized or cured directly upon and bonded to the metal sheet while in the flat. Preferably but not necessarily both sides of the flat metal sheet are so coated, so that the folded container will have a complete insulating lining on both its interior and exterior surfaces.

Hence a general object of the invention is to provide an improved form of sheet metal battery container which is fully protected from the acid used in the battery, which is leak-proof, and which can be made in a simple and economical manner.

Further objects and advantages of the present invention will be apparent from the following description, reference being had to the accompanying drawing, wherein a preferred embodiment of the present invention is clearly shown.

In the drawing:

Fig. 1 is a plan view of a three-cell storage battery container made according to this invention.

Fig. 2 is an end elevation of the container.

Fig. 3 is a section on line 3—3 of Fig. 1.

Fig. 4 is a perspective view of the partially formed container of Fig. 1, and shows the structure prior to the step of folding the eight outwardly projecting triangular metal folds to lie adjacent the cell walls to provide a neat box-like structure.

Fig. 5 is a plan view of the rubber covered flat sheet metal blank prior to the folding thereof. The dotted lines designate the various bend lines on the sheet.

Fig. 6 is a section on line 6—6 of Fig. 5 and shows a soft rubber coating vulcanized to both sides of the flat metal sheet.

Similar reference characters refer to similar parts throughout the several views.

The flat sheet metal blank 10, shown in Fig. 5, first has the insulating resilient coating 11 applied thereto, preferably on both sides thereof as shown. Preferably this coating 11 is of soft resilient rubber which is vulcanized directly upon the metal sheet 10 and thus strongly surface bonded thereto. The rubber-covered sheet 10 is then folded up by means of suitable dies along the various bending lines shown in Fig. 5. The three areas 1, 1' and 1'' become the bottoms of the three cells; while the areas 2, 2 become the two upstanding larger sides of the end cell A; areas 2', 2' become the two upstanding larger sides of the central cell B; and areas 2'', 2'' become the two upstanding larger sides of the end cell C. Part of areas 3, 3 become the two upstanding smaller side walls of cell A; the areas 3', 3' become the two upstanding smaller side walls of cell B; and part of areas 3'', 3'' become the two upstanding smaller side walls of cell C. Lines 4 designate the top edges of the two double thickness partition walls and extend completely across the blank 10, as clearly shown in Fig. 4.

Now when these upstanding side walls are folded to a vertical position the excess metal areas at each of the four corners of each cell is folded outwardly along the diagonal lines 5, 6, 7 and 8, thereby forming eight outwardly projecting triangular shaped metal folds 12 and 13 as clearly illustrated in Fig. 4. These triangular folds 12 and 13 obviously permit the side walls of each cell to be brought perpendicular to the bottom wall thereof without cutting away any of the metal area of the blank 10. It will also be noted that the structure shown in Fig. 4 forms three individual cells A, B and C having no intercommunication with each other, and each of which will not leak externally even though there has been no welding or other sealing of any seams. This is because all of the folds extend to the top edge of the cells, or in other words, there are no open joints below the top edge of the container.

Now to complete the forming of the container, the flat triangular projections 12 and 13 are folded up against the main side walls of the cells

A, B and C to provide a more compact and neat appearing structure and at the same time to materially increase the strength of the container. These projections 12 and 13 may be so 5 folded over to lie adjacent the main walls in any desired arrangement or manner of folding. However preferably the end projections 12 are first folded over to overlap each other and lie closely adjacent the ends 2 and 2" of the container as 10 shown in Fig. 1, and thereafter the adjacent two triangular projections 13 are folded around over the folded projections 12 at each opposed end of the container. In some cases, dependent on the relative dimensions of the container cells, 15 the projections 13 are sufficiently long to be made to overlap when folded around the ends of the container, as shown at 15 in Fig. 1. In such cases, if desired, these overlapping ends 15 may be spaced slightly from the ends of the 20 end walls of the container to provide convenient handles by means of which the storage battery may be lifted and moved around.

In all folding of the rubber-covered metal sheet the resilient rubber covering 11 will easily 25 distort at the bending lines and thus accommodate such folding without breaking or cracking or tearing loose from its bonded relation to the metal sheet at these lines of bending. In other words, the continuity of the insulating coating 11 will not be destroyed by any such folding as described above, and hence the finished battery container will have a complete insulating flexible lining throughout each cell. If desired, this insulating rubber lining may be used 30 only as an interior lining for the container and the outer surfaces of the metal container covered with any suitable acid-resisting coating after the container is completely formed as described. Of course the fundamental teachings of this invention can be applied to the making of a single cell container, and also to a multi-cell container having other than three cells.

Preferably soft steel sheet is used for the blank 10. The steel sheet may be coated with brass, 45 copper chloride, or a cement which will insure a firm bond of the rubber coating 11 to the metal. The rubber coating may be first applied to the metal sheet by calendering uncured rubber thereon so as to completely cover both sides and all 50 edges of the metal sheet, and then the rubber is vulcanized in place so as to provide a strong vulcanized bond to the metal sheet. This rubber covered sheet, illustrated in Fig. 6, is then 55 folded up as described above in a press by means of a series of forming dies in a manner which will now be clear to those skilled in this art.

While the embodiment of the present invention as herein disclosed, constitutes a preferred 60 form, it is to be understood that other forms

might be adopted, all coming within the scope of the claims which follow.

What is claimed is as follows:

1. The method of making a storage battery container, comprising: covering a flat metal sheet with a coating of resilient non-conducting material, then folding said coated sheet to form a seamless multi-cell structure having up-standing side walls and partition walls and outwardly projecting triangular metal folds at each 10 corner of the formed cells, then bending said projecting triangular metal folds to lie adjacent the main cell walls to form a box-like structure.

2. The method of making a storage battery container, comprising: covering a flat metal sheet with a coating of resilient non-conducting material, then folding said coated sheet along various lines to provide a multi-cell structure having up-standing double thickness partition walls 15 and single thickness outer side walls by forming outwardly projecting triangular metal folds at each vertical corner of the cells, then bending said projecting triangular folds to lie adjacent the side walls to form a box-like structure.

3. The method of making a storage battery container, comprising: covering a flat metal sheet with a coating of resilient non-conducting material, then folding said coated sheet to form a multi-cell structure having outwardly projecting triangular folds at each vertical corner with the resilient coating providing an interior lining for the cells, then bending the projecting triangular folds at some of the vertical corners of the cells to lie adjacent the side walls of the 30 container.

4. A storage battery container having a plurality of water-retaining cell compartments, said plurality of compartments having sheet metal side walls and bottom walls all folded from a single piece of sheet metal.

5. A multi-cell storage battery container folded up from an integral flat metal sheet, the partition walls separating the individual cells being formed of a double thickness of the metal sheet folded at the top edge of said partition walls.

6. A storage battery container having three water-retaining cell compartments, said three compartments having integral folded sheet metal side walls and bottom wall, and external triangular metal folds bent around the end walls 50 of the two end compartments to reinforce and strengthen the folded metal structure.

7. A multi-cell storage battery container folded up from a single metal sheet by forming outwardly extending triangular metal folds at the 55 vertical corners of each cell, said exterior triangular metal folds being bent to lie adjacent but exterior to the main cell walls to provide a box-like folded structure.
